UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

CUSHION HEEL.

Application filed December 11, 1922. Serial No. 606,195.

This invention relates to cushion heels and has for its object the improvement of such heels in respect to economy and facility of manufacture and ease of attachment.

Inasmuch as cushion heels are usually made of rubber or some material or composition having similar characteristics, the term "rubber heel" will, for convenience, be used herein to refer to such heels; but it should be understood that, wherever this expression is used in the following specification and appended claims, it is to be construed to cover a cushion heel made of any suitable resilient material having the general characteristics of rubber or rubber compositions.

Certain difficulties arise, both in the manufacture of the heel and in its attachment to a shoe, when a stiffening or supporting member or plate extending throughout an area including a plurality of the nailing locations is vulcanized into a rubber heel. Such a plate must be provided with holes for the passage of the heel attaching nails, and the first difficulty arises in locating the plate upon the supporting pins in the vulcanizing mold in which the heel is made. Under ordinary manufacturing conditions these molds are subjected to more or less rough treatment and the pins often become somewhat bent, with the result that a plate having holes of approximately the size of the pins and fixed as to spacing cannot be placed upon the necessary two or three pins, the spaced relation of which has been changed by one or more of them being bent. Another difficulty has its origin in the fact that the spacing between the pins in the heel mold is not the same as that of the holes in the nailing die of the heel attaching machine because, in the construction of such molds, the pins are spaced to allow for shrinkage of the heel in the curing process. It is, therefore, easily understood that a spacing and arrangement of holes in a stiffening plate which will fit the pins in the heel mold will not fit the pattern of the nailing produced by the heel attaching machine. If it be attempt to overcome these difficulties by making the holes in the stiffener oversize by a sufficient amount to insure the possibility of their being placed upon the pins in the heel mold and permit-

ting the heel attaching nails to be driven through them, failure will result because the holes will be so large that the heads of the attaching nails will pass through them, and the nails will have no substantial holding power in the rubber.

By the present invention a stiffening or supporting member, element, or plate is provided by which the above-mentioned difficulties are overcome without sacrificing the necessary anchorage for the heads of the attaching nails. In the illustrated embodiment of the invention, wherein three of the attaching nails pass through the stiffening element, elongated openings of a width just sufficient for the easy passage of the shank portions of the nails are provided. These openings may conveniently be in the form of slots through which the heads of the nails cannot pass. By arranging two of the slots approximately in alinement and a third slot at a right angle to the first two the maximum of efficiency is secured. The virtue of this novel construction and arrangement resides in the fact that the stiffening element may be placed easily upon the corresponding pins in the vulcanizing mold, regardless of variations in their spacing and will nevertheless be definitely located in the mold and held positively against horizontal movement in any direction; and furthermore that the attaching nails, whose spacing is determined by the spacing of the holes in the nailing die of the heelng machine, will easily find the apertures in the stiffening member and pass through them with certainty.

The ends of the stiffening member may advantageously project forwardly and lie quite close to the side edges of the heel at its breast corners, thus overcoming a difficulty met when trimming bases to which the rubber heels at present in use are attached. This difficulty arises from the fact that, when the shoe is presented to the heel trimming machine to trim the base to the contour of the rubber section, the comparatively soft rubber which serves as a guide for the top lift guard of the trimming cutter frequently yields at the breast corners sufficiently to permit the cutter to cut too deeply into the heel base, with the result that an excessive amount of scouring is required to produce a smooth, continuous surface around the edge of the heel, and the intended shape

of the heel is more or less departed from, usually to the detriment of its appearance. This trouble is eliminated by the heel herein disclosed, which cannot yield inwardly at the sides of the breast corners to any material extent, because the rubber is amply supported at these important places by the stiffening member.

While the embodiment of the invention herein illustrated and described in detail comprises a heel provided with a stiffening element located in and extending across the breast portion of the heel, and including the three breast nails, the invention is capable of many variations and may be embodied in heels having inserted elements of various other specific forms and in other possible locations.

The invention and its advantages will be more fully understood and appreciated by reading the following detailed description of one practical form thereof in connection with the accompanying drawings, in which

Fig. 1 is a plan view of the tread face of a rubber heel embodying the invention, with a portion broken away to reveal the internal construction;

Fig. 2 is a cross sectional view on the line 2—2 of Fig. 1;

Fig. 3 is a cross sectional view on the same line as Fig. 2, showing the heel attached to a shoe; and

Fig. 4 is a perspective view of the stiffening element or insert.

Referring now to the drawings, 10 indicates a cushion heel which may be of any desired or suitable thickness and may be a whole heel or a half heel. In the illustrated heel locations are provided for six attaching nails but it will be understood that the number of such nailing locations may be varied as desired. As shown, the nailing locations are designated in the usual manner by the provision of cavities or indentations 12, at the centers of which the nails are to be driven. In register with certain of the cavities 12 are nail engaging washers 14 of the usual form.

In the breast portion of the heel is a supporting and stiffening element 16, herein shown in the form of a relatively long and narrow metallic plate extending from one side to the other of the heel close to the heel breast and having pointed projections 18 extending laterally of the plate and reaching into the breast corners of the heel. The dimensions and contour of the element 16 are such that the flexibility of the heel apart from the breast portion thereof is unimpaired, and the ends of said element preferably lie quite close to the side edges of the heel at the breast corners.

20, 22 and 24 indicate the holes left in the heel by the pins in the rubber heel vulcanizing mold upon which the washers

are usually supported in the process of molding the heel. The plate 16 has three slots 26, 28 and 30 which are so arranged as to permit the plate to be placed upon and supported by the three mold pins last-mentioned. The width of these slots is the same as the diameter of the holes in the washers 14 and is sufficient to permit the passage of the shank of a rubber heel attaching nail, but not the head.

An important feature consists in arranging the central slot 28 at right angles to the slots 26 and 30, as shown. This makes it possible to place the plate 16 easily upon the three mold pins regardless of any inaccuracy in their spacing or any bending of the pins which may have occurred although after the plate is once located upon the pins the plate is securely held against horizontal movement in any direction. The plate and the washers 14 having been placed upon the pins in the heel mold the plastic material of which the heel is to be made is placed in the mold and the heel is then formed and vulcanized in the usual manner.

When the heel is attached to a shoe the three breast nails are driven through the slots 26, 28 and 30 respectively, the peculiar disposition and arrangement of the slots making it possible to easily align a sufficient portion of each slot with the corresponding hole in the nailing die of the standard commercial heeling machine to permit the nails to be driven through the slots with certainty, even though the spacing between the holes in the nailing die is not identical with that of the pins in the heel mold. The attaching nails, which are shown at 32 in Fig. 3, are driven and clinched in the usual manner. These nails place the plate 16 in a state of tension and, when the heel is normally concavo-convex in cross section, as illustrated, the plate will be somewhat deformed by the force exerted upon it by the attaching nails as they draw the rubber heel down flat against the heel base, which is indicated at 34 in Fig. 3. A comparison of Figs. 2 and 3 will show clearly how the plate 16 is sprung or bent when the nails are driven.

When the plate 16 is thus placed in a state of tension the projecting corners 18 draw the heel, particularly at its breast corners, down very tightly against the base. The plate 16 is preferably of spring steel in order that it may, when under tension, continue permanently to press the cushion heel tightly into engagement with the base to which it is attached. Experience has demonstrated that the attachment of this heel is so tight and secure that there is no necessity for the use of cement, and, consequently, a very material saving in the cost of the heel attaching operation is realized.

Apertures, such as slots 36, may be formed in the plate 16, permitting the rubber on op-

posite sides of the plate to meet and vulcanize together to afford a secure anchorage for the plate in the heel. These apertures are preferably located between the nailing slots, as shown, for the purpose of making the part of the plate between the slots 26, 30 more flexible than the projecting end portions of the plate, which are solid. The result of this is that the solid, relatively stiff, 10 end portions of the plate act, in a measure, as fulcra when the breast corners of the heel are pressed down tightly upon the heel base and the force exerted by the two nails driven through the slots 26, 30 has a tendency to 15 bend the middle of the plate toward the heel base, producing a tight joint across the breast even though, as is sometimes the case, the shank stiffener of the shoe projects rearwardly under the heel so far that it would 20 interfere with the center breast nail and the latter is consequently omitted.

The ends of the plate 16 are so close to the side edges of the heel at its breast corners that the rubber cannot yield inwardly 25 to any material extent when the heel is pressed against the top lift guard of the heel trimming machine, and the undercutting of the base, which is the cause of great annoyance in the trimming of bases to which 30 the rubber heels now in use have been attached, is prevented at and near the breast corners, which is the only place where the trouble is serious.

A cushion heel having on its tread face

designated nailing locations, at certain of 35 which are provided nail head engaging washers and at another of which is provided a stiffening member of larger area than one of the washers is not claimed herein but is claimed in my co-pending application, Serial 40 No. 607,077, filed December 15, 1922.

Having described the invention what is claimed as new and desired to be secured by Letters Patent is:

1. A rubber heel supporting or stiffening 45 element having a plurality of elongated nail receiving openings, two of said openings being substantially in alignment and another opening being substantially at right angles to the two first mentioned. 50

2. A rubber heel normally of curved cross section having therein a resilient, normally flat, stiffening element extending from side to side of the breast portion only of the heel and extending into the breast corners thereof, said heel being deformable to flatness, whereby the stiffening element is placed in a state of tension and the breast corners of the heel are pressed tightly against a shoe when the heel is attached to the shoe. 55 60

3. A rubber heel having therein an elongated, resilient, stiffening element extending from side to side of the breast portion only of the heel, said stiffening element being more flexible at its center than at its ends. 65

In testimony whereof I have signed my name to this specification.

JOHN B. HADAWAY.
